UNITED STATES PATENT OFFICE.

NOBLE G. ROSS, OF KANSAS CITY, MISSOURI.

VAPOR-BURNER.

SPECIFICATION forming part of Letters Patent No. 639,296, dated December 19, 1899.

Application filed May 26, 1899. Serial No. 718,344. (No model.)

To all whom it may concern:

Be it known that I, NOBLE G. ROSS, of Kansas City, Jackson county, Missouri, have invented certain new and useful Improvements 5 in Vapor-Burners, of which the following is a specification.

My invention relates to vapor-burners of that type wherein refractory mantles are used to produce an incandescent flame; and my object is to produce a vapor-burner whereby a 10 perfect combustion is obtained and the mantle rendered brilliantly incandescent throughout its entire surface.

With these objects in view the invention 15 consists in certain novel and peculiar features of construction and combinations of parts, as will be hereinafter described and claimed, and in order that the invention may be fully understood reference is to be had to the accompanying drawings, in which—

Figure 1 represents, mainly in side elevation, a vapor-burner and oil-tank constructed in accordance with my invention. Fig. 2 is a full size vertical section of the same. Fig. 3 25 is a vertical section taken in a plane at right angles to that of Fig. 2. Fig. 4 is a view of the burner mainly in top plan. Fig. 5 is a section taken on the line V V of Fig. 2.

Before proceeding with a detailed description 30 of the invention it is well to state that the two defects of burners of this class which I propose to remedy are caused by an imperfect or spasmodic generation of gas, thereby causing unsteadiness or irregularity in the pressure 35 and an imperfect combustion, due to the fact that the supply of air is not always proportionate to the supply or volume of vapor discharged into the mixing-tube. The cause of the irregularity in the pressure 40 and the disproportion of air and gas will be hereinafter pointed out in connection with the description of the construction whereby I remedy these defects.

In the said drawings, V B designate generally 45 my improved vapor-burner, of which 1 designates the mouth of the mixing-tube, 2 its neck or body portion, and 3 its enlarged or flaring head portion, the latter communicating with the combustion-chamber 4, formed 50 by the upwardly-projecting circular flange 4^a. The mouth 1 of the mixing-tube is of the same

width in one direction as its neck or body portion 2, but is of greater width in a plane at right angles thereto, so that its receiving end or mouth is of substantially oblong rectangular configuration, as shown most clearly in Fig. 5. Seated at the junction of the enlarged or head portion with the combustion-chamber is a burner-cap (designated generally by the letter C) consisting of the flat 60 metallic strip 5 and the crimped metallic strip 6, coiled or convoluted one within the other, as shown in Fig. 4. In a cap of this construction the interstices or openings are of sufficient length to give the gas as it passes up 65 through the same a vertical tendency, and thereby coöperate in the effort to render the mantle M, secured in position in the ordinary or any preferred manner, incandescent throughout its entire surface, it being 70 well-known that with the majority of vapor-burners at present in use the upper end of the mantle is not rendered perfectly incandescent. The wall at the inner side of the mixing-chamber is extended downward beyond 75 the flaring sides thereof and is provided with a vertical passage 7, and at its opposite side the wall is also extended downward and provided with a similar passage 8, said passages being connected at their upper ends by 80 the horizontal passage 9, (see Figs. 3 and 5,) to the end that the flame impinging directly upon the integrally-formed flange 4^a of the burner shall quickly raise the temperature of the latter sufficiently high to insure the thorough and quick vaporization of the oil in said passage and, by conduction, in the opening 10 communicating with the lower end of the passage 7. At the lower end of the passage 8 is an arm 11, forming a horizontal continuation 85 of passage 8, which continuation communicates with the vertical valve-seat passage and jet-orifice 12, arranged centrally below the mouth of the mixing-chamber.

13 designates an arm depending from the 90 inner end of the arm 11, and 14 an oil-cup adjustably mounted upon said arm, a threaded rod 15 extending vertically up through said cup and arm 13 and terminating at its upper end in a needle-valve 16, having its needle-point 17 normally projecting through the jet-orifice. By this needle-valve the jet-

orifice may be entirely closed, and by means of the needle-point 17 the orifice is kept free of obstructions to the passage of the gas.

As well known, the discharge of a jet of vapor through the air tends to push or whirl the air off at a tangent to the jet. As a consequence the volume of air ultimately mixed with the gas is too small proportionately to the volume of the latter and imperfect combustion results. This trouble occurs with any mixing-tube having a circular or substantially circular mouth of relatively large diameter, while, on the other hand, where the diameter of the mixing-tube is too small the same trouble occurs—that is to say, such a relatively large volume of air is whirled off at a tangent to the mixing-tube that there is an insufficient supply to support combustion in the combustion-chamber. By a great deal of experimenting I have discovered that I can obtain the requisite volume of air by providing a mixing-chamber having a mouth of the configuration shown and described—that is to say, a mixing-chamber having a mouth which 25 tapers at two sides from its receiving to its discharge end, while its opposite walls are substantially parallel. By this construction as the vapor is discharged into said flaring mouth the air at the narrow sides of the latter, the sides of the same extending downward to at least the plane of the jet-orifice, as hereinbefore described, and shown in Fig. 2, is held close to the burner and practically all of it is carried up by the frictional 35 action of the vapor-jet. At the opposite points the passage of the vapor-jet deflects a certain proportion of the air outward of the mouth of the mixing-tube, and, owing to the distance between the jets, the velocity of the air drawn in at these points is slow, which 40 is the reason why the mouth should be wide enough to take in a sufficient volume of air at the slow speed the latter is traveling. The rate of progress of the air of course increases 45 in proportion to the diminishing area of the mouth of the mixing-chamber, so that by the time it attains a speed about equal to that of the vapor it has entered, with the latter, the narrow or neck portion 2 of the passage, where- 50 in it is intimately intermixed with the vapor and carried up by the frictional action of the latter, the mixture forming a combustible gas, which burns in the chamber 4.

The air between the lower ends of the extensions of the side walls of the mixing-chamber mouth is held from the beginning in close frictional relation with the gas, and therefore gets up speed rapidly and, together with the proportion of air drawn up along the flaring 60 walls, insures the proper mixture of vapor and air and a perfect combustion, as will be readily understood.

18 designates the oil-supply pipe, which is closed at its upper end by a cap 19, secured thereto, said cap being in the form of a hook for convenience in suspending the burner or lamp. Near its upper end the lamp is pro-

vided with an aperture 18, and mounted upon the pipe and inclosing said aperture is an oil-tank 21, the latter being provided with 70 an internal partition, through which the pipe extends, said partition consisting of a pair of substantially parallel foraminous hoods 22, containing asbestos or equivalent packing 23 between them, the aperture 20 of the pipe 75 communicating with the space inclosed by the inner hood 22. This construction provides a filter to purify the oil before it reaches the pipe, and the inner hood prevents particles of lint from the packing 23 passing with 80 the oil into the hole or aperture 20.

The lower end of the pipe 18 communicates with the horizontal pipe 24, screwed into the burner and communicating with the chamber 10, and secured in this pipe is a device 85 which incidentally performs the function of a filter, but which is intended primarily to provide a continuous and uniform pressure by providing a constant generation of vapor.

In a number of vapor-burners with which 90 I am familiar the supply-pipe corresponding to pipe 24 is provided with a strainer, usually of wire, adapted to remove foreign substances from the oil and at the same time to so subdivide the stream of oil as to facilitate 95 its generation into vapor. With such construction, however, any excess of vapor generated creates a back pressure, which drives the oil back some distance, so that the pipe is at least partially filled with gas—that is to 100 say, its heated end is filled with gas—and in consequence the generative action for the fraction of a second ceases; but as the consumption of the gas continues this excess of pressure is eliminated at about the moment 105 the generation of the gas ceases, and at the same instant the oil which was pushed back by the excessive pressure flows forward again, but in a moment or so afterward is again pushed back, and thus oscillates back and 110 forth during the entire period the burner is in service. This oscillation of the oil in the pipe causes a blowing sound and spasmodic generation of gas, and this in turn causes an 115 irregularity in the pressure. My substitute 115 for this strainer or filter of the old burners prevents this irregularity of pressure and eliminates the disagreeable blowing sound by causing a constant and continuous generation of vapor, and its action will be ex- 120 plained after a brief description of its construction. It is constructed by placing upon a sheet of wire-gauze of suitable gage a slightly shorter sheet of asbestos or equivalent material and then forming a cylinder by 125 rolling the two sheets together, the sheets of gauze being designated by the numeral 25 and the sheets of asbestos by the numeral 26. The projecting ends of gauze are then bent 130 inward, so as to form the foraminous rear end 27 for the cylinder and the foraminous front end 27^a, the latter being so bent as to leave a little space between it and the adjacent end of the asbestos, so as to catch any lint or other

material which may work loose from the asbestos or other filling and prevent it from entering the vapor-passage. This construction permits the oil to enter and fill the burner, 5 as usual, and when the burner is heated sufficiently by oil burning in the cup 14 or by the flame impinging upon the flange 4^a the excess of vapor causes a back pressure, which drives the oil back some distance in the pipe 10 24, leaving the latter partially filled with gas, as hereinbefore described with reference to the old type of burner; but owing to the fact that the asbestos by absorption or capillary action remains saturated some distance in 15 advance of the oil itself the generation of vapor continues—that is to say, the heat of the tube adjacent to the burner evolves vapor from the oil-saturated end of the asbestos—which action continues until the excess 20 of vapor is consumed and by the lowering of the pressure the oil again rushes forward and crowds the vapor to such an extent that the latter pushes it back again, again leaving the front end of the asbestos saturated and ready 25 to continue the generation of gas.

From the foregoing it is obvious that the asbestos or equivalent material in the tube is the agent whereby the generation of gas is made continuous; but it is equally obvious 30 that the wire-gauze cage or its equivalent is necessary, as otherwise the burner would be speedily rendered inoperative by an accumulation of lint in the vapor-passage. Furthermore, by in effect weaving the gauze and asbestos together a substantially solid cylinder 35 is provided, which prevents the oil passing forward too rapidly. The constant pressure thus maintained, together with the proper mixture of air and vapor and the extended 40 vertical interstices of the burner-cap, insures the incandescence of the entire mantle; but in order to operate the burner as cheaply as possible by utilizing the heat for generating purposes I provide the cylindrical casing 28 45 to enclose the burner, said casing being formed with an offset 29 to receive the offset of the burner, which receives the pipe 24. The casing-offset is provided with a hole 30, through which the said pipe projects and is lined with 50 asbestos or equivalent material, as at 31, which by confining the heat serves to keep the casing of nice appearance, as well as to facilitate the vaporization of the oil.

From the above description, taken in connection with the drawings, it will be apparent that I have produced a vapor-burner which embodies the features of advantage enumerated as desirable in the statement of invention, and it is to be understood that I reserve 55 the right to make such changes as properly fall within its spirit and scope.

Having thus described the invention, what I claim as new, and desire to secure by Letters Patent, is—

1. A vapor-burner, provided with a mixing-chamber, comprising a neck or body portion and a flaring mouth communicating therewith, the receiving end of said mouth being of substantially elongated rectangular contour, substantially as described. 65

2. A vapor-burner, provided with a mixing-chamber comprising a neck or body portion and a substantially rectangular mouth, two sides of said mouth flaring outward, and the other two extending substantially parallel 70 and terminating beyond the termination of the flaring sides, substantially as described.

3. A vapor-burner, provided with a mixing-chamber comprising a neck or body portion and a substantially rectangular mouth, two 80 sides of said mouth flaring outward and the other two sides extending substantially parallel and beyond the termination of the flaring sides, said burner having its jet-orifice at a point between the terminals of the flaring 85 and straight sides of said mouth, substantially as and for the purpose described.

4. A vapor-burner provided with an oil-supply pipe and a cylinder fitting snugly in 90 said pipe and consisting of wire-gauze and an absorbent material; said cylinder being formed by placing a sheet of wire-gauze and a sheet of absorbent material together and then rolling them to cylindrical form, so that between the convolutions of the gauze occur 95 convolutions of absorbent material, substantially as described.

5. A vapor-burner, provided with an oil-supply pipe, and a cylinder fitting snugly in 100 said pipe and consisting of wire-gauze and an absorbent material rolled together; said wire-gauze being bent inward at its front end beyond the corresponding end of the absorbent material, substantially as described.

6. A vapor-burner, provided with an oil-supply pipe, and a cylinder fitting snugly in 105 said pipe and consisting of wire-gauze and an absorbent material rolled together; said wire-gauze being bent inward at its front end beyond the corresponding end of the absorbent 110 material, and bent inward at its rear end so as to cover the corresponding end of the absorbent material, substantially as described.

7. The combination with a vapor-burner, of a perforated supply-pipe having its upper 115 end closed and terminating in a hook, and an oil-tank mounted upon the pipe and inclosing its perforation, and provided with an internal partition consisting of a pair of foraminous hoods inclosing said hole, and a 120 filtration substance confined between said hoods, substantially as described.

In testimony whereof I affix my signature in the presence of two witnesses.

NOBLE G. ROSS.
